UNITED STATES PATENT OFFICE.

CHARLES T. DUNN, OF NEWARK, OHIO.

CLAMPING-MACHINE FOR PACKING-BOXES.

1,169,244.

Specification of Letters Patent.

Patented Jan. 25, 1916.

Application filed July 26, 1915. Serial No. 42,009.

To all whom it may concern:

Be it known that I, CHARLES T. DUNN, a citizen of the United States, residing at Newark, in the county of Licking and State of Ohio, have invented certain new and useful Improvements in Clamping-Machines for Packing-Boxes; and I do declare the following to be a full, clear, and exact description of the invention, such as will enable others skilled in the art to which it appertains to make and use the same.

My invention relates to improvements in devices for holding in position fiber or paper packing boxes and cartons, previous to filling the same and after the filling and sealing operation, whereby to retain the newly glued flaps in close contact until reliably adhered.

The object of the invention is to provide a machine of the class set forth which although being of comparatively simple and inexpensive construction, will be highly efficient and durable and will possess a number of advantageous features.

With this general object in view, the invention resides in certain novel features of construction and in unique combinations of parts to be hereinafter fully described and claimed, the descriptive matter being supplemented by the accompanying drawings which constitute a part of the application and in which:

Figure 1 is a side elevation of a machine constructed in accordance with my invention showing the application thereof to use in sealing a pair of cartons; Fig. 2 is a top plan view; Fig. 3 is a horizontal section as viewed along the plane indicated by the line 3—3 of Fig. 1; Fig. 4 is a central vertical longitudinal section taken on the plane designated by the line 4—4 of Fig. 2; Fig. 5 is an end elevation showing more particularly the relation of one of the locking levers with respect to one of the upper clamping plates, when the latter is raised; Fig. 6 is a vertical transverse section taken on the plane indicated by the line 6—6 of Fig. 1; Fig. 7 is a horizontal section viewed on the plane indicated by the line 7—7 of Fig. 1; Fig. 8 is a detail elevation of the upper end of one of the locking levers and a portion of one of the upper clamping plates, and Fig. 9 is a perspective view of one of such plates.

In describing the invention, I shall refer to these drawings by similar reference characters placed on corresponding parts throughout the several views, the numeral 1

designating an appropriate base from which an upright shaft 2 rises, said shaft being surrounded substantially throughout its length by a tubular standard 3 which is rotatable thereon. Having sockets receiving respectively the upper and lower ends of the standard 3, is an upper head member 4 and a lower head member 4^a, the two members being here shown as connected by a plurality of upright stay bolts 5, while in order to prevent removal of the standard 3 and its heads from the shaft 2, said shaft is shown as provided with a threaded stud 6 which projects loosely through a central opening in the upper head member 4 and receives thereon a nut 7 (see more particularly Fig. 4).

The head members 4 and 4^a include respectively horizontal angle iron bars 8 and 8^a, the former being secured to the upper side of the head member 4, while the bars 8^a are secured to the lower side of the head member 4^a. As clearly shown, two bars 8 are carried by the upper member in parallel relation, while two bars 8^a are disposed in such relation upon the lower head member. It is to be further noted that the bars 8 are disposed directly above the bars 8^a, this being expedient in order that the ends of a plurality of aligned upright rods 9 may be anchored to said bars, such rods constituting walls for contact with the cartons or boxes being clamped by the machine as will hereinafter become evident.

All of the bars 8 and 8^a are preferably of angle iron construction and the upright flanges of the bars 8 therefore constitute wall members for coaction with the rods 9, said flanges being shown in the present embodiment of the invention as having thereon a plurality of upright projections 10 which are normally received in notches 11, the latter being formed in one edge of a pair of vertically swinging upper horizontal clamping plates 12, said plates being hinged at 13 to the bars 8 as clearly shown in the several figures of the drawings. The projections 10 and the openings receiving the same therein are provided in order that when the plates 12 are opened as shown at the left of Fig. 4, sufficient space will not prevail between the bars 8 and said plates to allow one of the flaps of a carton to pass therebetween, thus always allowing the plates 12 to be readily disposed to horizontal position.

Disposed one beneath each plate 12, is a pair of relatively fixed horizontal clamping

plates 14, said plates being carried by arms 15 which radiate from a slide 16 mounted shiftable upon the standard 3, said slide having a nut 17 receiving therein an upright adjusting screw 18 whose upper and lower ends are swiveled respectively in the upper and lower heads 4 and 4^a and whose upper end is provided with an operating crank 19. Thus it will be seen that rotation of said 5 crank will raise or lower the plates 14 to adjust the machine for use upon boxes of different heights, yet that the upper ends of such boxes will be at all times disposed in the same horizontal plane, thus allowing the 10 same to be much more readily packed than would be possible were the tops of smaller boxes positioned lower than those of larger containers when being packed.

As clearly shown in Figs. 1, 2, 3, and 4, 20 the upper and lower clamping plates are provided with parallel slots 20 receiving therein clamping bolts 21 by which transverse cleats 22 are secured adjustably to the inner sides of said plates for engagement 25 with the outer sides of the cartons or boxes such as those disclosed at C in Fig. 1. Needless to say, containers of various sizes may be accommodated by proper adjustment of these cleats and the adjusting screw 18.

Projecting in opposite directions from the lower head member 4^a are the opposite ends 23 of a horizontal base frame which includes a pair of side bars 24 having parallel end portions and offset central portions, the former being connected by transverse bars 25, while said portions 24 are secured by bolts or the like to the aforesaid head 4^a. Spaced inwardly from the bars 25, transverse bearing members 26 span the gaps between the 30 parallel end portions of the bars 24, such members coöperating with the bars 25 to support a pair of horizontal rock shafts 27, said shafts having cranks 28 at their inner ends connected by links 29 with two slides 40 mounted on two of the upright stay bolts 5, such slides being in turn connected by links 45 31 to crank arms 32 which rise from the pivoted edges of the clamping plates 12.

Secured to the outer ends of the rock 50 shafts 27, is a pair of hollow upright lever sections 33 having therein longitudinal slots 34, said sections receiving slidably therein additional lever sections 35 having studs or other appropriate stops 36 disposed in the 55 slots 34 for allowing the two sections 33 and 35 to telescope, but for limiting the outward movement of one in respect to the other. When the plates 12 are lowered to active 60 position, the rock shafts 27 are so turned by the link connections between the crank arms 32 and 28, as to dispose the sectional levers in upright positions, whereupon appropriate latches 37 at the upper ends of said levers 65 may be engaged with headed studs or the like 38 on the plates 12 to prevent raising

of the latter. When, however, the plates 12 are to be lifted for the removal of the cartons beneath the same, the latches 37 are released, whereupon the sections 35 will drop by gravity into the sections 33, and the latter 70 will now be swung to horizontal positions when the plates 12 are raised, thus disposing the entire levers at such points as to prevent the same from interfering with the operator of the machine. When, however, the plates 75 12 are lowered, the levers are automatically returned to upright positions, whereupon the sections 35 are withdrawn and the latches 37 are again applied to use.

In addition to the features above described, an upright scale 39 is preferably provided, whereby the height of the lower clamping plates 14 may be accurately adjusted for the clamping of cartons of various sizes.

In operation, after first raising one or both of the movable clamping plates 12, a carton which is normally folded compactly, is opened into shape, is placed on one of the lower clamping plates 14, and what are 90 then the uppermost flaps of said carton are glued. The container is now inverted on the plate 14, being positioned between the rods 9 and the cleat 22, and is packed with the articles to be shipped, after which the top flaps are glued together, and the clamping plate 12 is moved downwardly and clamped. The entire machine is now swung horizontally upon the shaft 2, and the operation just described is repeated, the second carton being clamped between the other fixed and movable plates 14 and 12. By the time this second packing operation has been completed the glue on the first carton has sufficiently hardened to allow such carton to be removed, thereby allowing another one to be packed and sealed. Thus it will be evident that the operation of the machine is continuous with but one operator, and that practically no loss of time occurs.

In most cases, I prefer to carry the glue for sealing the cartons in appropriate glue pots 40 mounted upon the machine, but it will be evident that the glue could be obtained from other sources if desired.

From the foregoing description, taken in connection with the accompanying drawings, it will be evident that although comparatively simple and inexpensive construction has been provided, the invention will be highly efficient and durable and will possess a number of advantageous characteristics.

In the drawings, certain specific details of construction have been shown for accomplishing probably the best results, and in the preceding such details have been described, but I do not wish it understood that I am to be limited thereto otherwise than to the extent to which the appended claims restrict me. Furthermore, although the 125 130

drawings illustrate a machine having but two clamps, it will be evident that the same could be provided with any appropriate number.

5 I claim:

1. In a box clamping machine, an upright standard, a head member carried thereby including a horizontal bar, a series of upright rods depending from said bar and disposed in an upright plane to engage a box when clamped in the machine, an upper horizontal clamping plate pivoted at one edge to said bar, a lower horizontal clamping plate below the upper plate, and means 15 to lock said upper plate against movement. 70
2. In a box clamping machine, an upright standard, a head member carried thereby including a horizontal bar, a series of upright rods depending from said bar and disposed 10 in an upright plane to engage a box when clamped in the machine, an upper horizontal clamping plate pivoted at one edge to said bar, a lower horizontal clamping plate below the upper plate, a cleat carried by the 15 inner face of one of said plates and shiftable toward and away from the upright rods, and means to lock the upper plate against movement. 80
3. In a box clamping machine, an upright standard, an upper and a lower head member thereon, a series of aligned upright rods secured at their ends to said members and disposed in an upright plane to engage a box when clamped in the machine, an upper horizontal pivotally mounted clamping plate carried by the upper head member, a lower horizontal clamping plate below the upper plate, and means for locking said upper plate against movement. 85
4. In a box clamping machine, an upright standard, an upper and a lower head member thereon each including a horizontal bar, a plurality of upright rods secured at their ends to the two bars and disposed in an upright plane to engage a box when clamped in the machine, an upper horizontal clamping plate pivoted to the upper bar, a lower horizontal clamping plate beneath the upper plate, and means to lock the upper plate 105 against movement. 90
5. In a box clamping machine, an upright standard, an upper and a lower head member thereon, a series of aligned upright rods secured at their ends to said members, an upper horizontal pivotally mounted clamping plate carried by the upper head member, a slide shiftable vertically on the standard, an arm projecting horizontally from the slide between certain of the upright rods, a lower horizontal clamping plate carried by 110 said arm, means to lock the slide against movement on the standard, and additional means for locking the upper clamping plate against movement. 115
6. In a box clamping machine, a lower relatively fixed clamping jaw, an upper vertically swinging clamping jaw, a relatively fixed member, a vertically swinging lever fulcrumed to said member and disposed to upright position upon disposition of the upper jaw to horizontal position, and latch means on said lever for locking said upper jaw against raising. 120
7. In a box clamping machine, a lower relatively fixed clamping jaw, an upper vertically swinging clamping jaw, a relatively fixed member, a vertically swinging lever section fulcrumed to said member and disposed to vertical position upon disposition of the upper jaw to horizontal position, an additional lever section having a sliding engagement with the aforesaid section, and latch means on said additional section for locking said upper jaw against raising. 125
8. In a box clamping machine, a lower relatively fixed clamping jaw, an upper vertically swinging clamping jaw, a crank arm on the latter, a horizontal rock shaft below the two jaws having at one end a crank arm, a lever secured to the other end of said shaft, link means connecting the crank arm on the upper clamping jaw with the crank arm on the lever, whereby to dispose the latter to upright position upon disposition of said jaw to horizontal position, and latch means on said lever for holding 130 said upper jaw against raising. 95
9. In a box clamping machine, an upright wall member having on its upper edge a plurality of projections, a horizontal vertically swinging upper clamping plate hinged at one edge to said upper edge of the wall-member and having notches receiving the projections therein, a lower clamping plate below the upper plate, and means to lock said upper plate against raising. 100
10. In a box clamping machine, an upright shaft, an upright tubular standard revolvably mounted thereon, an upper and a lower head carried respectively by the upper and lower ends of said standard and each including a horizontal bar, a plurality of upright rods secured at their upper and lower ends to the upper and lower horizontal bars and disposed in an upright plane to engage a box when clamped in the machine, a horizontal upper clamping plate pivoted to the upper horizontal bar, a slide shiftable vertically on the tubular standard member, a lower horizontal clamping plate carried by the slide, means to lock said slide against movement on the standard, and additional means for locking the upper clamping plate against movement. 115
11. In a box clamping machine, an upright support, a frame member projecting laterally from the lower end thereof, a head member at the upper end of said support, a vertically swinging upper clamping jaw carried by the head, a crank arm on said 120
- 65 6. In a box clamping machine, a lower

jaw, a lower clamping plate beneath the upper jaw, a horizontal rock shaft mounted in the frame member and having at one end a crank, a lever secured to the other end of said shaft, link means connecting the crank arm on the upper clamping jaw with the crank arm on the rock shaft, whereby to dispose the lever to upright position upon disposition of said upper jaw to a horizontal

position, and latch means on the lever for locking said upper jaw against raising.

In testimony whereof I have hereunto set my hand in presence of two subscribing witnesses.

CHARLES T. DUNN.
